Primary Examiner — Holly E Thurman*Assistant Examiner* — Ieisha N Price(74) *Attorney, Agent, or Firm* — Merchant & Gould P.C.(57) **CLAIM**

The ornamental design for a corner key, as shown and described.

DESCRIPTION

FIG. 1 is a perspective view of a corner key.

FIG. 2 is a front elevation view of the corner key of FIG. 1. FIG. 3 is a rear elevation view of the corner key of FIG. 1. FIG. 4 is a right elevation view of the corner key of FIG. 1. FIG. 5 is a left elevation view of the corner key of FIG. 1. FIG. 6 is a top plan view of the corner key of FIG. 1; and, FIG. 7 is a bottom plan view of the corner key of FIG. 1. The broken lines depict portions of the corner key that form no part of the claimed design and the dot-dot-dash lines define the boundaries of the corner key that form no part of the claimed design.
